MACHINE FOR SCORING ICE BY FLUID-PRESSURE MEANS

Application filed October 31, 1927. Serial No. 229,913.

This invention relates to machines for scoring ice in blocks, so that the blocks may thereafter be readily broken into smaller blocks of desired size.

5 The primary object of the invention is to provide an ice scoring machine with hydraulic or pneumatic means for handling the ice blocks before or after the process of scoring or during such process as may be desired.

10 The machine is capable of operation by hydraulic water pressure as a supply of water under pressure is available at an ice making factory. However, if it is desirous of operating the machine herein described in an ice 15 vault or in any other location where there would be danger of the water freezing, or of moisture in the air freezing, the machine can be operated by oil or other non-freezing fluid under pressure.

20 The invention will be clearly understood from a perusal of the following detailed description, taken in connection with the accompanying drawings forming part of this specification and wherein:

25 Figure 1 is a longitudinal sectional view of the machine, some portions being shown in elevation.

Figure 2 is a horizontal sectional view taken along the line 2—2 of Figure 1.

30 Figure 3 is an end view of the elevator cage for lifting a block of ice for engagement with the saws.

Figure 4 is a detail view of means for engaging a block of ice in moving the block to 35 or from the machine.

Figure 5 is a detail sectional view of the lower part of the framework and showing a hydraulic cylinder.

Figure 6 represents a block of ice which has 40 been scored by the machine.

Figure 7 is an enlarged detail view of a modification similar to the lower part of Figure 1, and showing a horizontal cylinder for moving a block of ice to or from the machine.

45 Figure 8 is an end view of the elevator cage, the view showing a modification of the panel or bottom of the cage.

Figure 9 is a detail view of a valve for controlling the hydraulic pressure.

50 Figures 10 and 11 are sectional detail views

of the valve Figure 10 showing the valve in position to raise the ice and Figure 11 showing the valve in reverse or exhaust position.

Proceeding in accordance with the drawings and wherein different numerals denote the various parts of the machine, 1 denotes a framework having a platform or support for the motors 2. The motors are connected to drive the shafts 3, one on each side of the machine, journalled in the bearings 4, and which carry the rigidly mounted saws 5 which score the ice block crosswise. On one end of the shafts 3 are disposed bevel gears 6 in mesh with similarly constructed gears 7. The gears 7 are mounted on the vertical shafts 8, upon which are rigidly mounted saws 9, the saws 9 being for the purpose of scoring the blocks of ice 8^a lengthwise. In this arrangement it will be obvious that the machine is capable of scoring the ice blocks crosswise only, as indicated at 10, lengthwise only, as at 11, or both lengthwise and crosswise, as may be desired.

Referring to Figure 1, on top of the framework is mounted a hydraulic cylinder 12, including a piston rod 13 having a piston inside the cylinder. The piston rod 13 is attached to an elevator cage consisting of the spaced vertical members 14, connected by the bar 15 and the lower ice-supporting element or panel 17. The piston rod 13 is connected to the bar 15 by the link 16.

Connected to the cylinder 12 is a pipe 18 which leads to a fluid pressure supply of any preferred form. In the pipe line 18 is a valve 19, shown in detail in Figure 9 and in section in Figures 10 and 11. Connected to the valve is also an exhaust pipe 20. The valve includes an operating handle 21. On the valve stem 22 is a disk 23 provided with a notch 24. The valve mechanism also includes a weighted lever 25 and a lever 26, the lever being normally held in the notch by a spring 27. On the piston rod 13 is a trip member 28. These parts will be referred to hereinafter in the operation of the machine.

The valve 19 is seated in a housing 29 which includes the inlet port 30, outlet port 32 and exhaust port 33, and the valve is provided with ports 34, 35 and 36 which when 100

registered in the positions shown permit inlet of fluid pressure through the valve to the cylinder and from the cylinder to exhaust as shown in the drawings.

The invention also provides means for carrying a block of ice into the machine, or from the machine which is provided for by the horizontal cylinders 37, hereinafter referred to more particularly, or the ice may be handled manually as preferred. From the foregoing description it will be readily seen that it is possible to remove the horizontally disposed saws and by the operation of the vertical saws score the ice blocks vertically only. It is also possible to operate the machine in such a manner that the ice blocks could be scored horizontally after being scored vertically, or by placing the ice in at the opposite end of the machine, the ice blocks could be scored vertically before being scored horizontally.

By reference to Figures 4 and 5 it will be seen that the cylinder 37 has a piston rod 38 and on which is rigidly attached a trip member 39. The liquid pressure pipe 18 is connected to the cylinder 37 by a lateral 39' and wherein is arranged a valve 40. The lateral 39' also has connection 39'' with the exhaust pipe 20. Attached to the opposite end of the cylinder is also a pipe 41' which on operation of the valve will move the piston in this cylinder to normal position, i. e., that shown in Figure 1. Operation of the valve 40 will admit liquid pressure to move the rod 38 to place the trip 39 behind a block of ice as indicated at A in Figure 2. Reverse movement of the valve will then draw or slide the block of ice in over the platform 41—the trip 39 moving through the slot 42.

Ordinarily a block of ice may be placed on the platform 41, moved inward by the trip 39, thence into the cage 14, where it is elevated and scored crosswise by the saws 5, then lowered, the saws passing through the kerfs cut. Then the block of ice is or may be drawn outward by moving the ice from the cage by hand along the platform to delivery, without scoring it longitudinally. The trip 39 has a weighted end 39^a and the block of ice when pushed against the trip in one direction will cause the trip to tilt over and will right itself when the end of the block has passed over it—the pin 39^b then holding the trip upright to bear against the ice.

In Figure 8 is shown a modification of the cage or lifting means and wherein the bottom or panel 17 is grooved through its entire length at 17^a to permit the trip 39 to move clear through the machine. In this manner a block of ice may be scored longitudinally only and passed from end to end of the machine—the reception being at one end and delivery effected at the other. Figure 7 shows the position and arrangement of the cylinder 37,

rod 38, trip 39 and longitudinal groove 42 for bringing this about.

The machine may be operated with or without the use of the horizontally disposed cylinder or cylinders, just as desired. In operation of the machine without the horizontal cylinder, the operator places a block of ice in the elevator cage, which is then in its lowermost position and opens the valve 19 by manipulation of the handle 21. This admits liquid pressure under the piston in the cylinder 12, whereupon the cage and block of ice are raised. The ice is then scored crosswise or vertically by the saws 5, the block rising until the lower edge of the ice is level or about level with the horizontal saw shafts. Now the block could be lowered by a reverse movement of the handle 21, but to enhance the practicability and usefulness of the machine, there is provided the arrangement shown in Figure 9. In this arrangement, when the operator pulls the handle 21 to open the pressure control valve 19, it is held in open position by the lever 26, the dog 26^a falling into the notch 24 on the disk 23, and when the elevator has reached its highest ascending point, the trip 28 on the rod 13 comes in contact with the lower end of the lever 26. This lifts the dog from the notch and the weight 25 returns the valve to normal closed position again, permitting ice and elevator to descend. When the ice has returned to its original position at the bottom of the machine, it can be removed by hand, another block inserted and the process repeated. It will be readily understood that when operated in this manner it would be possible to remove the horizontal saws and by operating the vertical saws, score the ice blocks vertically only. It is also possible to operate the machine in such a manner that ice blocks could be scored horizontally after the vertical scoring operation, or by placing the ice blocks in at the other end of the machine the blocks could be scored vertically before scoring horizontally.

Referring to the valves 19 and 40, it will be obvious from Figures 10 and 11 that when liquid pressure is admitted through pipe 18 to the right in the drawing, such pressure will pass through the valve and lift the piston in cylinder 12, and that when the dog 26^a is released, the valve will then assume the position shown in Figure 11, i. e., the exhaust liquid passing into the pipe 20, the port 34 being closed.

Practically the same operation will take place in the valve 40, this valve being operated by the handle 40^a, but being a fourway valve. Thus when pressure is admitted through the valve 40 by moving the handle 40^a, such pressure will pass from the pipe 18 to the pipe 29', through the valve, thence into the cylinder, moving the piston to the opposite end and forcing the exhaust through the valve into pipe 39', thence into pipe 20. This op-

eration will of course be reversed when the piston has moved to the opposite end of the cylinder.

The machine is capable of further modifications in keeping with the spirit of the invention and in keeping with the scope and meaning of the appended claim.

What is claimed is:

In an ice scoring machine, an ice carrier 10 adapted to be raised vertically for scoring the ice, a single fluid pressure cylinder mounted above said carrier, and having a piston rod connected at its lower end to the carrier, a trip carried by said piston rod, a valve for 15 controlling the pressure to said cylinder, a pivoted dog for holding said valve in position to supply pressure to the cylinder, said dog having a lever arm extending into the path of said trip, whereby the dog will be 20 withdrawn and the valve released as the piston rod is raised to a predetermined level, and means for closing the valve as soon as the valve is released.

In testimony whereof we affix our signatures.

GEORGE BRAUNGART, JR.
